SANITARY RUBBER SHEET

John H. Johnson, Toronto, Ontario, Canada

Application January 16, 1941, Serial No. 374,677

2 Claims.

(Cl. 5—334)

This invention relates to improvements in the manufacture of rubber sheets particularly those used in hospitals but which are applicable for use in many other ways, and the principal objects of the present invention are to provide a sheet which will effectively resist the deteriorating effect of acids and which will be capable of being thoroughly sterilized and is sanitary in every respect.

A still further object is to produce a sheet which will not slip or creep on a mattress when placed upon a bed and which further will permit the free placement and adjustment of the ordinary linen or cotton sheets thereover.

The principal features of the invention consist in the novel manner of fabricating the sheet whereby the fabric reinforcement is completely sealed within a rubber coating so that access of acids and other destructive fluids will be prevented from destroying the fabric reinforcement.

A further important feature consists in producing a sheet with an extremely smooth face on one side and a definitely uniformly roughened face on the other side.

Further important features consist in the novel steps in the method of producing a sheet as hereinafter described and claimed.

In the accompanying drawing

Figure 1 is a perspective view showing the manner of assembling the several elements that make up the composite sheet.

Figure 2 is a perspective view illustrating the manner of treating the composite sheets immediately following the assembly of the several elements.

Figure 3 is a perspective view illustrating the manner of securing and sealing the edges of the sheet.

Figure 4 is a perspective view showing the manner of forming a uniformly roughened surface on the back of the sheet.

Figure 5 is an enlarged sectional detail of one of the edges of the completed sheet showing the sealing of the edge thereof.

In the manufacture of the rubber sheets herein described it is found desirable to coat the reinforcing fabric sheet 1 by spreading thereon a thin coating of a rubber solution of a suitable consistency. This coated sheet is then placed upon a thin rubber sheet 2 and a rubber sheet 3 50 is then placed thereover and the whole is suitably calendered.

The calendered sheet is then laid upon an enamelled metal plate 4 and the composite sheet is then carefully rolled to remove all air from 55

underneath the same and to press out any ridges or inequalities in the surface of the underside which is in contact with the smooth enamelled face.

5 Following the careful rolling of the sheet the edges thereof are turned inwardly and folded down tightly as illustrated in Figure 3 and after the edges 5 have been inturned, thin rubber strips 6 are laid over the edges of the inturned portions so as to completely overlie and cover the exposed edges of the fabric reinforcement 1.

After these covering strips 6 have been placed in position a sheet of coarse woven fabric 7 is laid over the previously completed sheet and the entire sheet is then placed in a press along with the enamelled metal plate 4 and when pressure is applied thereto the imprint of the coarse fabric sheet is pressed into the unvulcanized rubber sheet, thereby applying a textile formation 20 on the surface which will present a rough friction surface which will prevent the completed sheet from slipping when placed upon a mattress.

25 After pressure has been applied the coarse textile sheet is stripped from the rubber sheet which still adheres to the enamelled plate and the enamelled plate and rubber sheet pressed thereto is placed with others in a vulcanizing chamber where it is subjected to the required temperature and pressure to vulcanize the entire mass, and the top and bottom covering sheets with their infolded edges and overlaid sealing strips are all securely vulcanized and the completed sheet is thus thoroughly sealed against 30 ingress of moisture at any portion contacting with the fibrous reinforcement.

Further, the vulcanizing of the sheet in direct contact with the extremely smooth enamelled surface of the metal plate provides one 40 surface of the rubber sheet with a smooth shiny surface which will offer the least possible resistance to slippage and a rubber sheet is produced which has a rough opposite surface adapted when placed downwardly against a mattress to prevent the sheet from slipping on the mattress. At the same time the composite sheet will present a smooth topside which will permit cotton or linen sheets to be pulled thereover with ease and there will be no fabric in the rubber sheet exposed to absorb acids or to become contaminated with germs. Consequently the sheet can be thoroughly sterilized by immersion in sterilizing solutions or by heat treatment as may be desired.

What I claim as my invention is:

1. A sanitary rubber sheet comprising a sheet of textile material having a thin sheet of rubber on each face thereof, said rubber sheet being of substantially equal thickness, the composite sheet having its edges turned over to form a friction margin to hold the sheet in position on a bed and the turned-over edges being vulcanized flat to the sheet, the extremities of the edges being overlaid with a sealing rubber strip to protect the textile fabric against the ingress of moisture.

2. A sanitary rubber sheet comprising a sheet

of textile material having a thin sheet of rubber covering each face thereof, said composite sheet having its edges folded inwardly to form a thickened frictional margin, the inner extremities of the turned-over edges being overlaid with a sealing rubber strip to protect the textile fabric against the ingress of moisture or germs, one face of the fabricated sheet being formed with a roughened surface similar to that of a coarse textile fabric, the other face presenting a smooth shiny surface.

JOHN H. JOHNSON.
